APPLICATOR HEAD FOR FOUNTAIN
BRUSHES

Arthur B. Davies, Pittsburgh, Pa.

Application April 10, 1947, Serial No. 740,526

2 Claims. (Cl. 15—114)

1

This invention relates to a cleaning device, more particularly a fountain-fed rubbing or scrubbing member which utilizes dry cleaning fluids for removing spots from clothing and the like.

The invention will become more apparent from a consideration of the accompanying drawing, constituting a part hereof, in which like reference characters designate like parts, and in which

Fig. 1 is an exploded view of a fountain-type cleaning device showing a fluid chamber and receptacle housing in vertical section, a cleaning head, and a cap therefore in side elevation;

Fig. 2 a bottom plan view of the face of the cleaning head taken along the line 2—2, Fig. 1;

Fig. 3 a vertical cross-sectional view, partially in elevation, of a modified form of such cleaning device; and

Fig. 4 a vertical cross-sectional view, partially broken away, of still another modification of the cleaning device.

With reference to Fig. 1 of the drawing, the numeral 1 designates a casting having a cylindrical housing 2 formed integrally therewith, the open end of the housing 2 being provided with an end cap 3 and a screw thread stopper 4. A receptacle 5 is integrally formed with the casting 1 and divided from the cylindrical housing portion 2 by a partition 6 having a fluid flow passage 7 controlled by a valve 8 having screw thread engagement at 9 through the wall of the implement, valve 8 being provided with a knurled head 10 for adjusting relative to the flow passage 7 to control the flow of fluid from housing 2 to the receptacle 5. The receptacle is provided with a bead 11 and an inner thread 12 for receiving a ferrule 13 of a cleaner head, as is more clearly shown in Fig. 3 of the drawing, the ferrule 13 being provided with a knurled flange 14 for gripping by the hand to screw the head into the receptacle as shown in the assembly of Fig. 3.

Ferrule 13 surrounds a rubber ring 15 having rubber bristles 16 extending thereon and in which is embedded a sponge rubber mass 17 cut out at 18 to form a chamber for receiving the liquid from the flow passage 7. The sponge rubber mass completely fills the receptacle chamber to seal off the fluid flow which is absorbed by the sponge rubber to moisten the face or surface 19, Fig. 2, which is applied to the soiled spot on the clothing to be cleansed.

In the form of structure shown in Fig. 3, a cleaning head 20 is provided with a threaded portion 21 to receive the threaded end of a fluid container 22 which takes the place of the housing

2

2 in the structure of Fig. 1. In this form of the device the dry cleaning fluid may be sold in bottles of the shape of member 22 or in any other convenient form with a screw thread of a size to fit the threaded portion 21 of the cleaning head, thus avoiding the annoyance of charging the cleaning fluid into the cylindrical housing portion 2 through the opening in the end cap 3 thereof. When not in use, the cleaning head is covered by a cap 23, Fig. 1, which slips over the knurled flange 14 of the rubber retaining ferrule 13.

In use the device of Fig. 1 is charged with a suitable dry cleaning fluid through the opening in the end cap 3 by removing the knurled screw 4, 15 after which it is sealed by the latter. The cleaning head has previously been assembled in the receptacle portion 5 by screwing the ferrule 13 in the threaded portion 12, the sponge rubber mass 17 being of such length as to contact the face 20 of the partition member 6 and displace the rubber to fill the entire receptacle chamber. In this manner the sponge rubber acts as a seal against the free flow of the cleansing fluid from passage 7 into the receptacle 5. At the same time, the sponge rubber or other compressible absorbing material becomes saturated with the cleansing fluid and the working face 19 is moistened thereby for application of the fluid to the spot to be treated. Valve 8 is adjusted to supply 30 a desired degree of cleansing fluid to the cleaner head face and the user rubs the soiled surface with the cleansing head bringing the rubber bristles 16 in contact with the soiled spot to cleanse the same. When not in use the valve 8 35 is closed and the end cap 23 is placed over the cleaning head so that the device may be safely stored anywhere even though charged with the fluid.

In the form of the device shown in Fig. 3, the 40 dry cleaning fluid may be supplied in special containers or bottles having a threaded end for interacting with the thread of the head 20. In this manner the need for charging the fluid into the fluid chamber is eliminated. Otherwise the 45 construction and operation of the cleaning head and fountain is as described in connection with Fig. 1.

In Fig. 4 the screw threaded opening 25 for valve 26 is isolated from the source of cleaning 50 fluid in chamber 27 so none can leak out through the thread 25 when valve 26 is closed on its seat 28.

Although several embodiments of the invention have been herein illustrated and described, 55 it will be evident to those skilled in the art that

various modifications may be made in the details of construction without departing from the principles herein set forth.

I claim:

1. In a fountain cleaning device having a threaded receptacle for an applicator head, of a metal ferrule having a threaded body for screwing into the receptacle and a compressible relatively dense rubber annulus disposed within the threads of the ferrule and having rubber bristles extending outwardly therefrom, and a sponge rubber mass contained within said annulus extending outwardly to the end of the bristles and extending inwardly beyond the end of the ferrule into the receptacle chamber to completely fill 15 said receptacle.

2. An applicator head for fountain cleaning devices having a receptacle with a threaded inner wall which consists of a threaded ferrule for interacting with the threads of the receptacle, an annulus having bristles extending outwardly therefrom and secured in said ferrule, and a sponge rubber mass filling said annulus and ex-

tending outwardly to the end of said bristles and inwardly beyond said ferrule to completely fill the receptacle.

ARTHUR B. DAVIES.
